UNITED STATES PATENT OFFICE.

JOSEPH F. LANGER, OF MILES CITY, MONTANA.

COMBINED ROAD GRADER AND ROLLER.

1,106,951.

Specification of Letters Patent. Patented Aug. 11, 1914.

Application filed November 4, 1912. Serial No. 729,257.

To all whom it may concern:

Be it known that I, JOSEPH F. LANGER, a citizen of the United States, residing at Miles City, in the county of Custer and State of Montana, have invented certain new and useful Improvements in Combined Road Graders and Rollers; and I do hereby declare the following to be a full, clear, and exact description of the invention, such as will enable others skilled in the art to which it appertains to make and use the same.

My invention relates to that type of machine generally designated as road graders, and has for its object to simplify and improve the construction thereof, and also to provide features which adapt the machine for use as a roller.

To the above ends, generally stated, the invention consists of the novel devices and combinations of devices hereinafter described and defined in the claims.

In the accompanying drawings which illustrate the invention, like characters indicate like parts throughout the several views.

Referring to the drawings, Figure 1 is a view in side elevation showing the improved machine; Fig. 2 is a plan view of the same, some parts being removed; Fig. 3 is a transverse section taken on the line $x^3 x^4$ on Fig. 2 looking rearward; Fig. 4 is a transverse section taken on the said line $x^3 x^4$ looking forward; and Fig. 5 is an enlarged detail view partly in elevation and partly in vertical section on the line $x^5 x^6$ on Fig. 2, with some parts being broken away.

Preferably, I employ a truck structure of a type adapted for use as a traction engine, when equipped with the proper motive force, such as afforded by an explosive engine or a steam engine. Of the parts of this truck, the numeral 1 indicates the framework, and the numeral 2 the rear axle equipped with wide-faced traction wheels 3, the pivoted front axle 4, and wide faced, but relatively small wheels 5 loosely journaled on the said axle. The said pivoted front axle 4 is shown as of a cast yoke-like structure provided with a spindle 6 upon which the wheels 5 are directly journaled. When the machine is used as a roller, supplemental front wheels 7, diagrammatically shown in Fig. 2, are adapted to be applied on the spindle 6 between the outside front wheels 5. When the wheels 5 and 7 are applied on the spindle 6,

they constitute a sectional roller which is wide enough to roll the space which is between and which is not traveled by the main traction wheels 3. Thus it will be seen that said main traction wheels 3 coöperate with 60 wheels 4 and 5 in the rolling action.

The numeral 8 indicates a long and stiff scraper blade which is carried by the truck and is adjustably supported thereby, through connections, preferably arranged as 65 follows:

The numeral 9 indicates a pair of forwardly converging thrust bars, the front ends of which are connected to the back of the scraper blade 8, inward from the ends 70 thereof, by ball and socket connections 10, best shown in Fig. 5. The rear end portions of these thrust bars 9 are attached to the ends of two chains 11 and 12, which chains are passed around and adapted to be 75 moved by peripherally notched sheaves 13 and 14 secured to a vertical shaft 15 journaled in suitable bearings on the transverse yoke 16 of the main frame 1. At its upper end, the said shaft 15 may be provided with 80 a hand wheel or with any other suitable means for oscillating the same.

Extending parallel to the scraper blade 8 and mounted for angular movements in ground yokes 17 secured on the side bars of 85 the frame 1 is a horizontal beam 18 shown as made up of laterally spaced channel bars. To the central portion of this beam 18 is rigidly secured a center bearing plate 19 to which is pivotally connected a lower bearing 90 plate 20. The beam 18 is intermediately pivoted at 21 (see Fig. 4) to transverse beams 1^a of the frame 1. In this way, the beam 18 is supported for horizontal angular or pivotal movement, but is held against vertical movements and against endwise movements. The said beam 18 is caused to partake of the horizontal angular movements of the scraper blade 8, by means of rods 22 pivotally connected thereto and to the thrust 100 bars 9. The scraper blade is held against endwise movements transversely of the machine, by means of oblique brace rods or bars 23, shown as pivotally connected to the front ends of the thrust bars 9 and to 105 projecting lugs 20^a on the pivotally movable plate 20. The oblique rods 23 hold the scraper blade 8 against endwise movements in respect to the oscillatory beam 18, and the pivoted plate 20 acts as an equalizer 110

and moves pivotally when the scraper blade is raised or lowered in respect to the said beam 18.

The pivotal connections between the brace rods 23 and lugs 20^a are very loose, so that there will be no binding action when the rods 23 change their angle in respect to a horizontal plane. To set the scraper blade at any desired pitch or scraping angle in respect to the ground, the upper edge thereof is connected to the front ends of the thrust bars 9, by means of longitudinally adjustable bars 24. These bars 24 are shown as made up of sections mounted to slide, one upon the other and having perforations through any one of which a pin 26 is adapted to be inserted to maintain the longitudinal adjustment of the said bars.

Swivel blocks 27 are pivotally connected to the ends of the oscillatory beam 18, and vertically extended screw-threaded adjusting rods 28 are swiveled in the said blocks 27, being held against vertical movements by collars 29 on the said rod. At its upper end, these rods 28 are shown as provided with end wheels 30, by means of which they may be rotated and their threaded lower ends work in internally threaded sleeves 31, the lower ends of which are loosely pivoted to the front ends of the thrust bars 9.

The operation of the machine, briefly described, is substantially as follows: By oscillations of the shaft 15 and the sheaves 13 and 14 thereon, the chains 11 and 12 may be manipulated so as to simultaneously force one of the thrust bars 9 ahead and the other thrust bar 9 rearward. In this way, the scraper blade may be set to work either at a right angle in respect to the direction of travel of the machine or at any angle in respect to the direction of travel, receding rearward toward either side of the machine. The connecting rods 22, as already stated, cause the beam 18 to partake of the horizontal angular movements of the said scraper blade, so that the adjusting rods 28 will always be held in vertical positions. By rotation of both adjusting rods 28 in the same direction, both ends of the scraper blade may be raised or lowered and set either in an elevated inoperative position, or to scrape to any desired extent the surface of the ground traveled by the machine. By uneven, or different movements of the said adjusting rods 18, the one end of the scraper blade may be raised more than the other and the scraper blade thus set to round over or bevel the sides of the road or to do other work requiring the scraper blade higher at one end than at the

other. Obviously, the forming of embankments or trenches will require one end of the scraper blade to be adjusted much higher than the other. It will thus be seen that all of the adjustments required in a finishing road grader or scraper are provided for by an extremely simple and efficient mechanism capable of easy manipulation. In fact, the entire machine is of comparatively small cost and generally efficient for the purposes had in view.

What I claim is:

1. In a grader, the combination with a truck, of a scraper blade, an oscillatory member carried by the said truck, oblique rods pivotally connected at their inner ends to said oscillatory member on opposite sides of its axis, and connected at their outer ends to said scraper blade, thereby holding said scraper blade against endwise movements transversely of the machine, and means holding said scraper blade in different horizontal angular adjustments.

2. In a grader, the combination with a truck, of a scraper blade, an oscillatory member carried by the said truck, oblique rods pivotally connected at their inner ends to said oscillatory member on opposite sides of its axis, and connected at their outer ends to said scraper blade, thereby holding said scraper blade against endwise movements transversely of the machine, and means holding said scraper blade in different horizontal angular adjustments, a device for vertically adjusting said scraper blade, and devices for imparting horizontal oscillatory or angular adjustments thereto.

3. In a grader, the combination with a truck and a beam mounted on the framework thereof for horizontal oscillatory movements, of a scraper blade below said beam, thrust bars connected to said scraper blade on opposite sides of its center, a pivoted member connected to the central portion of said oscillatory beam, oblique rods connected at their inner ends to said pivoted member and connected at their outer ends to the front end portions of said thrust bars, vertically adjustable screw connections between the ends of said beam and said scraper blade, rods connecting said thrust bars to said oscillatory beam, and means for simultaneously forcing one of said thrust bars forward and the other rearward.

In testimony whereof I affix my signature in presence of two witnesses.

JOSEPH F. LANGER.
